UNITED STATES PATENT OFFICE.

PHILLIP J. SWEARINGEN, OF LOS ANGELES, CALIFORNIA.

DESIGN FOR A BOX.

47,440.

Specification for Design.

Patented June 8, 1915.

Application filed February 15, 1915. Serial No. 8,385. Term of patent 14 years.

To all whom it may concern:

Be it known that I, PHILLIP J. SWEARINGEN, a citizen of the United States, residing at Los Angeles, in the county of Los Angeles and State of California, have invented a new, original, and ornamental Design for Boxes, of which the following is a specification, reference being had to the accompanying drawing, forming part thereof.

The figure is a perspective view of a box illustrating my new design.

I claim:

The ornamental design for a box as shown.

PHILLIP J. SWEARINGEN.

Witnesses:

EDMUND A. STRAUSE,
MARGUERITE BATES.
